UNITED STATES PATENT OFFICE.

DICK B. WILLIAMS, OF SCOTTDALE, PENNSYLVANIA, ASSIGNOR OF ONE-HALF TO JOSEPH R. STAUFFER, OF SCOTTDALE, PENNSYLVANIA.

CLAY-TREATING FURNACE.

No. 799,127.

Specification of Letters Patent.

Patented Sept. 12, 1905.

Application filed April 16, 1904. Serial No. 203,520.

To all whom it may concern:

Be it known that I, DICK B. WILLIAMS, a citizen of the United States, residing at Scottdale, in the county of Westmoreland and State of Pennsylvania, have invented certain new and useful Improvements in Clay-Treating Furnaces, of which the following is a specification.

This invention relates to the treatment of clays for the production of a highly indurated and refractory product possessing utility as an abrasive and for a variety of other uses.

To this end the invention primarily has in view a simple and practical type of furnace or apparatus designed for manufacturing in quantities the new clay product disclosed in the related application filed July 2, 1903, Serial No. 164,079, and in the companion application filed of even date herewith.

20 A special object of the invention is to provide a furnace wherein the process of manufacturing the said product can be carried out with the instrumentalities which have been found to secure the best results in the final product, or, in other words, to provide perfected means whereby the dried clay form may be subjected to the exclusive action of the carbonaceous gas from an incandescent body of coke in physical contact with the form 25 and while sealed from extraneous sources of oxygen.

With these and many other objects in view, which will more readily appear as the nature of the invention is better understood, the same 30 consists in the novel construction, combination, and arrangement of parts, which will be hereinafter more fully described, illustrated, and claimed.

The essential feature of the invention involved in the relation of the interior charge-chamber to the enveloping fuel-chamber about the same is necessarily susceptible to structural modification without departing from the scope of the invention; but a preferred embodiment of the present invention is shown in the accompanying drawings, in which—

Figure 1 is a vertical sectional view of a clay-treating furnace constructed in accordance with the present invention and shown in its charged condition. Fig. 2 is a similar view illustrating a convenient method of charging or filling the furnace. Fig. 3 is a cross-sectional view on the line 3-3 of Fig. 2, illustrating

ing the charge-former in position prior to its removal from the furnace.

55

Like numerals designate corresponding parts in the several figures of the drawings.

The clay product resulting from the process carried out by the present invention possesses certain distinct and marked characteristics and advantages over the products ordinarily known as "carborundum," "siloxicon," and the like, and to distinguish the same from such analogous products I have termed it "carboclay," inasmuch as the latter results from the chemical change caused in clay material by the exclusive action of the carbonaceous gas evolved from a highly-heated body of carbon, (preferably coke.) This is quite distinct from those known processes provided for various combinations of carbon, silica, and oxygen, inasmuch as the present invention involves a treatment of the clay material wherein the carbonaceous gas, excluded from possible union with oxygen from extraneous sources, effects the peculiar chemical change in the clay material which from experimental analyses has been found to be deficient in carbon and yet at the same time having a remarkable degree of hardness and 70 heat-resisting qualities and also being distinctly an abrasive to a high degree.

To successfully produce the carboclay or clay product referred to, the process steps primarily resorted to consist in taking the form 85 or body of clay material and drying the same, then embedding the dried form in an envelop of carbon (preferably coke) confined in a sealed chamber, next completely surrounding the sealed chamber with an envelop of fuel-coke, 90 and, finally, firing the latter to bring the confined carbon or coke to an incandescent state until the clay form is converted into the hardened product of carboclay.

In all of the experiments so far tried the 95 best product is obtained by subjecting, as stated, the dried form to the action of the carbonaceous gas evolved from a confined body of coke brought to a state of incandescence while on, against, or about the clay form and 100 in direct physical contact therewith. However, in no experiment has this incandescent body of coke or carbon been found to mix, adhere, or attach itself in any way to the clay form. Hence there is no mixing whatever, 105 and the chemical changes are brought about

entirely through the action of the carbonaceous gas.

Since the above conditions are the best so far known for carrying out the process, the 5 furnace of the present invention has been designed particularly with a view of embodying those conditions.

Referring to the drawings, showing the furnace in simplified form, the numeral 1 designates an upright furnace-casing having the 10 walls thereof made of suitable refractory material capable of withstanding intense heat and made of any desired size or shape. However, a substantial and well-reinforced casing 15 or body can be provided by making the same of a rectangular shape in cross-section, as shown in Fig. 3 of the drawings, and in the construction selected for exemplifying the invention the furnace casing or body 1 is provided with an open top portion 2, adapted 20 to be completely inclosed and sealed while the furnace is in operation by a removable dome-cover 3, having a refractory lining 4 corresponding to that of the body of the furnace and also provided at the top with a lifting-eye 5, which may be engaged by suitable lifting-tackle for handling the cover. Also in 25 the plane of the open top portion 2 of the furnace casing or body there is preferably built a charging-platform 6 to facilitate the introduction of the charge into the casing.

A distinctive feature of the furnace structure resides in providing the same with an interior charge-chamber 7, corresponding in 35 cross-sectional form to that of the furnace casing or body 1, but of a narrower width and less height, whereby there is provided entirely about the said chamber 7 an enveloping fuel-chamber. All portions of the interior 40 enveloping fuel-chamber are in direct communication, so that upon charging fuel through the open top of the furnace-casing the same will reach every part of the fuel-chamber, which lies at the sides, top, and bottom of the 45 interior charge-chamber 7.

The interior charge-chamber 7 is formed of refractory material throughout, and essentially consists of the upright connected side walls 8 and the closed bottom 9, united with 50 the walls 8. In this formation the interior charge-chamber 7 is provided with an open top 10 and immediately above the plane of its closed bottom 9 is formed in one side thereof with a test-opening 11, piercing the wall 55 of the furnace casing or body and designed to be closed during the operation of the furnace by a temporary plug or closure 12, of clay or equivalent material, such as usually employed for similar purposes in metallurgical furnaces.

To thoroughly reinforce the structure, the interior charge-chamber 7 has extended from the corners thereof the reinforce or brace webs 13, which join the side walls of the furnace-casing, but yet at the same time leave

open pockets or spaces constituting parts of the fuel-chamber at the sides and corners of the charge-chamber 7.

Within the bottom portion of the furnace are arranged a series of supporting-arches 14, 70 arising from the base of the furnace and joined to the closed bottom 9 of the charge-chamber 7. The supporting-arches are preferably made of refractory material and are arranged in spaced relation with the intervals 17 there- 75 between of sufficient size to accommodate one or more bars of the fuel-grate 15, suitably supported within the bottom portion of the furnace-casing above the ash-pit 16. By reason of this spaced relation of the supporting-arches 14 the intervals therebetween are in 80 direct communication with the side portions 18 of the fuel-chamber, so that the fuel introduced into such side portions will also fill into the bottom fuel-spaces 17 at the bottom of the 85 charge-chamber.

The top portion of the furnace-casing above the charge-chamber 7 is occupied by the top fuel-space 19 of the fuel-chamber. This top fuel-space 19 is in communication with the 90 smoke or gas flue 20, leading off to the stack 21.

In carrying out the present invention it may be found desirable to employ an ash-pit 16 of a closed type and having connected therewith a blast-pipe 22 for supplying blast to the 95 fire in order to secure the high degree of heat necessary for securing proper results.

The clay material may be charged into the chamber 7 in any convenient manner, such as suggested in the drawings. This expedient, 100 which may be resorted to, consists in employing a charge-former 23, consisting of a bucket or vessel corresponding in cross-sectional form to that of the charge-chamber 7 and of a sufficient capacity for holding the entire charge 105 of clay material to be treated. This bucket or vessel constituting the charge-former may be provided at the top with a lifting-bail 24 for attachment thereto of the lifting-tackle 25 for raising and lowering the same. Also 110 in the type of charge-former 23 shown in the drawings the same may be provided with a temporary releasable bottom 26. This temporary releasable bottom 26 may be held to the body of the former and released therefrom 115 by any suitable means. However, for illustrative purposes the same is shown as having a wedging fit on the bottom edges of the former-body and of greater width than the latter to provide the projecting flange edges 120 upon which the coke or carbon filling is packed and will hold the said bottom at the bottom of the charge-chamber when the charge-former is removed. This is only suggestive, but is sufficient for illustrative purposes, and it 125 should also be noted that the temporary releasable bottom 26 is formed of wood, so that it will simply be reduced to charcoal by the firing of the furnace.

The dried clay material may be placed into 130

the charge-former in any suitable way; but a practical method is shown in the drawings, and consists in filling the former 23 with alternating layers of clay material and crushed 5 or powdered coke 27 and 28, respectively, so that each section or form of clay material will have a body of coke or carbon in direct physical contact with the top and bottom thereof, as plainly shown in both Figs. 1 and 10 2 of the drawings.

While the charge-former is in position a coke or carbon filling 29 is packed about the same; but before completely filling the charge-chamber the former is withdrawn, after which 15 the crushed coke or carbon is packed into the open top of the charge-chamber, as at 30, thereby sealing in the charge. After thus introducing and packing the charge in the furnace the entire fuel-chamber, made up of 20 the spaces 17, 18, and 19, is filled with fuel-coke, making a complete envelop for the charge and its containing-chamber. The fuel is next fired to bring the confined coke or carbon about the clay material to a state of 25 incandescence, in which state it is maintained until the clay is converted into the hardened product of carboclay herein described.

Various changes in the form, proportion, and minor details of construction may be re- 30 sorted to without departing from the spirit of the invention or sacrificing any of the many advantages thereof.

Having thus described the invention, what is claimed, and desired to be secured by Letters 35 Patent, is—

1. A furnace of the class described, comprising a closed casing having a permanent

interior refractory charge-chamber, and a fuel-chamber entirely enveloping the latter.

2. A furnace of the class described, comprising a casing, a closed refractory charge-chamber, and a fuel-space about the top, sides and bottom of said charge-chamber. 40

3. A clay-treating furnace comprising a closed refractory casing, and a permanent interior refractory charge-chamber arranged to receive the clay material and a filling of coke, 45 said charge-chamber having an open upper end, opening into the fuel-space, and spaced from the walls and bottom of the furnace-casing to leave an enveloping coke-chamber thereabout. 50

4. A furnace of the class described comprising an upright covered furnace-casing provided with a fixed interior chamber of less 55 height and width than the same, said charge-chamber being open at the top and provided with a side test-opening at the bottom and with bracing webs in the interval between the same and the furnace-walls, a series of 60 supporting-arches adjoining the bottom of the charge-chamber and arranged in separated relation to provide intervening fuel-spaces in communication with the fuel-spaces at the sides of the charge-chamber, and a 65 blast connection with the furnace-casing at the bottom thereof.

In testimony whereof I affix my signature in presence of two witnesses.

DICK B. WILLIAMS.
